UNITED STATES PATENT OFFICE.

JAMES FRANKLIN CHILCOTE, OF PORTLAND, OREGON.

LEVER MECHANISM.

965,082.

Specification of Letters Patent. Patented July 19, 1910.

Application filed December 20, 1909. Serial No. 534,066.

To all whom it may concern:

Be it known that I, JAMES F. CHILCOTE, a citizen of the United States, and a resident of Portland, in the county of Multnomah and State of Oregon, have invented certain new and useful Improvements in Lever Mechanism, of which the following is a specification.

My invention is an improvement in lever mechanism, and consists in certain novel constructions, and combinations of parts hereinafter described and claimed.

The object of the invention is to provide a simple lever mechanism for operating the winding gear of a hoisting engine, or similar devices, wherein both the winding drum and the tripping drum are operated by a single lever, thus leaving one hand of the engineer free for other purposes, as, for instance, to handle the throttle.

Referring to the drawings forming a part hereof:—Figure 1 is a side view of the improvement. Fig. 2 is a plan view partly in section. Fig. 3 is a detail perspective view of a portion of the operating mechanism, and Fig. 4 is a side view of the same.

In the present embodiment of the invention, the hoisting drum 1 and the tripping drum 2 are mounted on a single shaft 3, which is journaled in bearings 3^a on a frame consisting of side plates 4 and 5, which are secured to the floor or other supports by bolts 6.

The drums 1 and 2 are loosely journaled on the shaft, and each drum is provided, on its inner end, with an annular marginal flange 7 having a collar 8 secured thereto, the inner surface of which is conical, as shown. The collar is of material having a high coefficient of friction, and forms one portion of a friction clutch.

A disk 9 is secured on the shaft between the drums and is provided with an annular series of crown teeth 10, and on each side of the teeth with a conical projection 11 adapted to engage the inner surface of the collar 8, when the adjacent drum is moved toward the disk, and clutch the said drum to the disk and to the shaft.

50 A drive shaft 12 is journaled in front of the shaft 3 and parallel therewith in bearings 13 on brackets 13^a, and the shaft is provided with a pinion 14 meshing with the crown teeth of the disk. A disk 15, provided with a wrist pin 16, is secured on

each end of the drive shaft outside of the bearings 13.

A guideway 18 is supported on a base 19, near each side plate, and a block 20 is slideable in each guideway. A cylinder 21 is supported on each base 19, and the piston rod 22 of the cylinder is connected with one end of the adjacent block, and the block is connected by a link 23 with the wrist pin 16 of the adjacent disk.

A counter or operating shaft 24 is journaled in bearings 25 on the side plates, in front of the drive shaft, and an arm 26 is secured to one end of the shaft outside of the bearings. A block 27 is adjustably secured to the other end by a set screw 28, and an arm 29 is secured diagonally to the outer face of the block by bolts or rivets 30.

The drums are movable longitudinally of the shaft 3 to connect them to and disconnect them from the disk, and are operated by means of the usual screws 43 and 43^a, the screw 43 operating the hoisting rope drum, and the screw 43^a the tripping rope drum. A lever 31 is provided at one end with a grip 32, and at the other with a split bearing 33 which engages the outer end of the screw 43, and a bolt 34 is provided for clamping the sections of the bearing on the screw. The lever is further secured by a key 35.

A substantially triangular plate 36 is provided at its base end with openings 37 for receiving bolts 38, whereby it may be secured to the lever, and the apex end of the plate is provided with a lateral flange 39 through which is threaded a set screw 40. A link 41 is pivoted by one end, as at 42, to the plate near the apex end, and the opposite end of the link is pivoted to the outer end of the arm 29, before mentioned.

The screw 43^a has secured to the outer end thereof an arm 44, which is connected by a link 45 with the arm 26 on the shaft 24. The cylinders 21 are supplied with motive fluid through the pipes 46 from any suitable source, and are of any usual or desired construction.

In operation, the motive fluid is admitted to the cylinders, and the blocks or cross heads 20 are reciprocated in the guideways, thus rotating the driving shaft 12, and through the intermeshing of the pinion and crown teeth, the disk is also rotated. The hoisting rope and the tripping rope are 110

connected with their respective drums, so that when the drums rotate, they will be wound or unwound in accordance with the direction of rotation.

5. It will be observed that the connection between the shaft 24 and the screws 43 and 43^a is such that when the said shaft is oscillated toward the left in Fig. 1, the screw 43 is turned in one direction, while the 10 screw 43^a is turned in the other, so that when the said shaft is oscillated in either direction, one screw will be operated to connect its drum with the disk, while the other will be operated to disconnect its drum from 15 the disk.

When the lever 31 is moved into the position shown in full lines in Fig. 1, the hoisting drum is connected with the disk, and the tripping rope drum is disconnected, 20 while when the lever is moved into the position shown in dotted lines, the tripping rope drum is connected and the hoisting rope drum disconnected. When the lever is moved into the intermediate position, 25 both drums are disconnected.

The arrangement of the flange 39 and the set screw 40 limits the movement of the lever, by its engagement with the link 41, as indicated in Fig. 4. It will be evident from 30 the description, that a means is provided for simultaneously moving the drums in the same direction, so that when one is engaged with the driving means, the other will be disengaged therefrom.

35 I claim:—

1. In a device of the class described, a plurality of drums, a common operating means for the drums, a lever for connecting one of the drums with the operating means, an 40 arm for connecting the other drum with the operating means, a shaft parallel with the drums and having at each end an arm, said

arms being at right angles to each other for the purpose specified, a connection between one of the arms and the drum operating arm, a plate connected to the lever, said plate having at its upper edge an overhanging flange, a link connecting the other arm of the shaft with the plate intermediate its ends, and a set screw threaded through the 50 flange and engaging the link.

2. In a device of the class described, a plurality of drums, a common operating means for the drums, a lever for connecting one of the drums with the operating means, an 55 arm for connecting the other drum with the operating means, a shaft parallel with the drums and having at each end an arm, said arms being at right angles to each other for the purpose specified, a connection between 60 one of the arms and the drum operating arm, a plate connected to the lever and extending toward the shaft, a connection between the other arm of the shaft and the plate, and means on the plate for limiting 65 the movement of the link in one direction.

3. In a device of the class described, a plurality of drums, a common operating means for the drums, a lever for connecting one of the drums with the operating means, an 70 arm for connecting the other drum with the operating means, a shaft parallel with the drums and having at each end an arm, said arms being at right angles to each other for the purpose specified, a connection between 75 one of the arms and the drum operating arm, a connection between the other arm and the lever, and means for limiting the movement of the lever and the said arm with respect to each other.

JAMES FRANKLIN CHILCOTE.
